UNITED STATES PATENT OFFICE.

AMOS HARRISON, OF CHICAGO, ILLINOIS, ASSIGNOR OF ONE-FOURTH TO
ROBERT H. WALCH, OF CHICAGO, ILLINOIS.

LOW-PRESSURE HEATING SYSTEM.

No. 812,926.

Specification of Letters Patent.

Patented Feb. 20, 1906.

Application filed August 26, 1904. Serial No. 222,197.

To all whom it may concern:

Be it known that I, AMOS HARRISON, a citizen of the United States of America, residing at Chicago, in the county of Cook and State 5 of Illinois, have invented certain new and useful Improvements in Low-Pressure Heating Systems, of which the following is a description.

My invention relates to a system of heating 10 apparatus wherein the heating medium consists of a suitable vapor under low and preferably approximately atmospheric pressure.

The object of my improvement is to provide substantially automatic means for circulating such a medium at low pressure without the necessity of a pump or fan except at 15 possibly infrequent periods in starting the operation.

To this end my invention consists in the 20 novel construction, arrangement, and combination of parts herein shown and described, and more particularly pointed out in the claims.

In the accompanying drawings, wherein 25 like or corresponding reference characters indicate like or corresponding parts, Figure 1 is a diagrammatic elevation of a heating system embodying my invention, certain parts being in section to more clearly show the construction. Fig. 2 is an enlarged sectional view showing a part of the construction of the pressure-reducing means. Fig. 3 is a sectional view showing a detail of connecting certain parts. Fig. 4 is a vertical section of 30 the preferred generator. Fig. 5 is a transverse section on line 5-5 of Fig. 4, and Fig. 6 is a diagrammatic view showing a modified arrangement of my device.

In the preferred form shown in the drawings, 1 is a generator of any suitable construction connected by a main 2 to suitable radiators. As shown in Fig. 6, the radiator 3 is connected by what is known as a "single-pipe" system, while in Fig. 1 the connection 35 with the radiator 4 indicates the two-pipe system. The two methods are shown to indicate the preferred connection in each instance. It is of course obvious that any number of radiators may be employed and 40 that either the single-pipe or two-pipe systems may be employed, as desired.

Attached to the main 2 in any preferred

manner is an automatic pressure-reducer comprising a casing 5, suitably connected at one end to the main, as at 6, and closed at its 55 opposite end upon a centrally-contained tube or pipe 7. One end of the tube 7 forms a connection with an extension 10, preferably passing transversely through the main 2, as shown. Thus while the medium may circulate freely about the tube it is prevented from passing into it. By this means the tube is heated and the passing partially cooled vapor therein is increased in temperature above that which is conducted thereto from 60 the radiators.

That part of the tube 7 extending outside the casing 5 is preferably extended a short distance above the roof of the building in which the apparatus is located, so that any 70 air, gas, or vapor within the tube may be freely discharged into the atmosphere. In order to assist this action, I prefer to place upon the projecting end of the tube an ejecting-cowl 8, provided with a suitable vane 9, 75 the two being rotatably mounted to secure the most favorable action of the wind.

In the preferred form shown the pipe 10 forms an extension or continuation of the tube 7 and is provided with a suitable trap 80 or seal 12 and connected with a pipe 11, arranged to return any fluid arising from condensation in the system to the generator.

In order to communicate the partial vacuum or reduced pressure within the tube 7 and associated parts to the radiators and various parts of the system to cause the vapor to flow therein, I connect the radiators by a suitable pipe or pipes 14 to the tube 7 or extensions thereof above the highest point to 90 which liquid therein will rise. If desired, automatic "air-valves" 15, operated by the temperature in the usual manner, may be located at suitable points in the system to regulate the flow of vapor in the pipes and 95 prevent waste.

I prefer to provide a trap 16 in each pipe 11 near the generator and in other parts of the system where fluid is likely to accumulate, and provide the same with drip-cocks 100 17, so that the system may be drained when desired.

A pipe 18 is provided with a valve 19 and arranged to conduct the liquid to be vapo-

rized to the generator. If preferred, a vacuum-breaker 20 of suitable construction may be positioned in the main and the usual valves employed to control the flow of vapor in the system.

If preferred, a vacuum-pump or an exhaust-fan 21 (see Fig. 6) may be provided and suitably connected in the system to induce a proper circulation in the system in case of emergency or in starting the operation.

Any preferred form of generator suitable for the purpose may be employed. Satisfactory results may be secured by means of the generator shown in Figs. 5 and 6, made the subject-matter of a separate application for Letters Patent duly filed August 1, 1904, Serial No. 219,007.

As shown, the shell 22 is provided with one or more transversely-arranged porous beds 23 of incombustible material, which are raised to high temperature by a burner 24, adapted for use with gas, oil, or the like. The fluid is introduced by a pipe or pipes 11 and distributed by a foraminated annular trough 25 or, if preferred, by a spraying-nozzle 26. (Shown in dotted lines.) The vapor generated is intimately mixed with the products of combustion from the burner, and the mixture thus formed is passed into the system by means of the pipe 27, connecting with the dome 28. The burner may be open to the atmosphere by means of a suitable opening 29 or other preferred means.

Obviously the highest economy is secured, inasmuch as the products of combustion, as well as the generated vapor, pass through the system and give up their heat in their passage through the system, as described.

Having thus described my improvement, it is obvious various immaterial modifications may be made without departing from the spirit of my invention. Hence I do not wish to be understood as limiting myself to the exact form and construction shown.

What I claim as new, and desire to secure by Letters Patent, is—

1. A device of the kind described, comprising radiators, conducting-pipes, and a generator for producing a heating medium, in combination with an automatic pressure-reducer and discharge-pipe, consisting of a tube open at one end, means for heating said tube by said heating medium, and means connecting various parts of the system to the other end of said tube to induce a flow of the heating medium to those parts.

2. A device of the kind described, comprising radiators, conducting-pipes, and a generator for producing a heating medium, in combination with an automatic pressure-reducer and discharge-pipe, consisting of a substantially vertical tube open at its upper end to the atmosphere means for heating said vertical tube by means of said heating

medium and induction-pipes connecting the lower end of said vertical tube with various parts of the system to induce a flow of the heating medium to those parts.

3. A device of the kind described, comprising radiators, conducting-pipes, and a generator for producing a heating medium, in combination with an automatic pressure-reducer and discharge-pipe consisting of a substantially vertical tube open at its upper end positioned partly within a casing connected to said conducting-pipes, whereby said vertical tube is heated by said heating medium, and induction-pipes connecting the lower end of said vertical tube with various parts of the system to induce a flow of the heating medium to those parts.

4. A device of the kind described, comprising radiators, conducting-pipes, and a generator for producing a heating medium, in combination with an automatic pressure-reducer and discharge-pipe consisting of a substantially vertical tube open at its upper end and provided with a suitable ejector-cowl, means for heating said vertical tube by means of said heating medium and means connecting various parts of the system to the lower part of said vertical tube to induce a flow of the heating medium to those parts.

5. A device of the kind described, comprising radiators, conducting-pipes, and a generator for producing a heating medium, in combination with an automatic pressure-reducer and discharge-pipe consisting of a substantially vertical tube open at its upper end and provided with a suitable ejector-cowl, means for heating said vertical tube by means of said heating medium, and induction-pipes connecting the lower end of said vertical tube with various parts of the system to induce a flow of the heating medium to those parts.

6. A device of the kind described, comprising radiators, conducting-pipes, and controlling means and a generator for producing a heating medium, in combination with an automatic pressure-reducer consisting of a substantially vertical tube open at its upper end and provided with a suitable ejector-cowl, said vertical tube being positioned partly within a casing connected to said conducting-pipes, whereby said vertical tube is heated by said heating medium, and induction-pipes connecting the lower end of said vertical tube with various parts of the system to induce a flow of the heating medium to those parts.

7. An automatic pressure-reducer, comprising a tube adapted to be placed in a substantially vertical position, an air-tight casing inclosing a part of the length of said tube, means for connecting said casing to a conducting-pipe whereby a heating medium is admitted to said casing to heat said tube and

means for connecting induction-pipes to the lower end of said tube.

8. An automatic pressure-reducer, comprising a tube adapted to be placed in a substantially vertical position provided with an ejector-cowl at its upper end, a casing inclosing a part of the length of said tube, means for connecting said casing to a conducting-pipe, whereby a heating medium is admitted to said casing to heat said tube, and means

for connecting induction-pipes to the lower end of said tube.

In testimony whereof I have hereunto signed my name in the presence of two subscribing witnesses.

AMOS HARRISON.
